UNITED STATES PATENT OFFICE.

JOHN MCKEOUGH, OF BURLINGTON, VERMONT.

PORTABLE FOLDING CAMP-BEDSTEAD.

SPECIFICATION forming part of Letters Patent No. 337,415, dated March 9, 1886.

Application filed May 4, 1885. Serial No. 164,391. (No model.)

To all whom it may concern:

Be it known that I, JOHN MCKEOUGH, a citizen of the United States, residing at Burlington, in the county of Chittenden and State 5 of Vermont, have invented certain new and useful Improvements in Portable Folding Camp-Bedsteads, of which the following is a specification, reference being had therein to the accompanying drawings.

10 My invention relates to improvements in portable folding bedsteads designed especially for camp or hospital use; and it consists of two principal sections or divisions hinged to a common supporting central frame, each section being supported by legs so hinged to its outer extremities that the entire bedstead can be compactly folded into the form of a rectangular box, which can be readily packed away or transported. The entire frame is suitably 15 braced, strong, of simple and cheap construction, and portable, as will be hereinafter more fully set forth.

My invention is fully shown in the accompanying drawings, in which similar letters 20 indicate like parts.

Figure 1 is a perspective of my bedstead when extended for occupancy or for ambulance purposes. Fig. 2 is a similar view of the same when folded and ready to be carried.

25 A and B are the two sections which form, when extended, the bedstead. They are constructed with the usual side and outer end pieces, *a a* and *b*, *c c* and *d*. The interior extremities of their side pieces, *a a* and *c c*, 30 rest upon the center legs, *C C*, to which they are attached by the metallic plates *e e*, which are fastened to the outside of the upper end of the legs *C C*, and to which they are so pivoted at *f f* that they can be folded down upon

35 the legs *C C*. When the sections are extended horizontally, they are securely held by means of the hinged braces *g g*, which are pivoted to the inner side of the side pieces and center legs. In a similar manner the end supports, 40 *D D'*, are so pivoted to the metallic plates *h h'*, which are firmly attached to the outer ends of the side pieces, *a a* and *c c*, respectively, that they can be folded into the recesses *i i* and *i' i'*, which are cut into the lower edges of 45 the side pieces, the length of the recesses being that of the legs *D D'*, and their depth being sufficient to receive that portion of the

width of the legs *D D'* which projects beyond the width of the center legs, *C C*, when the two sections of the bedstead are compactly 55 folded together, as shown in Fig. 2. When opened, the legs are firmly held by the hooks *p*. The several pairs of legs are firmly braced together by the cross-bars *kk*, which are placed below the point of depression of the sacking 60 or carpet when the bed is used. This sacking material is so attached to the top of the frame of each of the sections A and B that sufficient allowance is made for the quantity of the material required to be taken up in the center 65 when the bed is folded, as shown in Fig. 2.

G is a pillow or bolster consisting of a frame whose ends are pivoted to the side pieces, *a a*, at *m*. It is covered with cloth or other elastic material. By means of a ratchet-wheel and 70 pawl on its pivoted extremities the frame can be raised or lowered to any angle desired, as shown in Fig. 1.

H H' are handles so pivoted to the inside of the end legs, *D* and *D'*, that they can be 75 elevated to a horizontal position against the lower edge of the end pieces, *b* and *d*, for the purpose of convenience in carrying the bed by hand when the frame is extended. When not required, they can be turned down on the 80 inside of the legs, as indicated by dotted lines in Fig. 1.

When the bed is compactly folded, as described, and as shown in Fig. 2, sufficient space is afforded in its interior for all necessary bedding.

The two sections A and B are held together by hooks *s*, and the handle I is added to facilitate its being carried when folded compactly.

What I claim, and desire to secure by Letters Patent, is—

1. In a portable folding bedstead, the combination of the sections A and B, having legs *D D'* pivoted to their outer extremities, the legs being provided with pivoted handles *H H'*, the legs *C C*, having hinged braces *gg* connecting them with the side pieces, *a a* and *c c*, the whole being constructed and arranged in the manner substantially as and for the purposes set forth.

2. The combination of the sections A and B, pivoted to the plates *e*, attached to the center legs, *C C*, so that they can be folded down against the legs *C C*, and having their side

pieces suitably recessed at *i i* to receive the folding legs D D', the legs C being provided with hinged braces *g g*, to more firmly secure the sections A B in a horizontal position, and 5 the legs D D' having pivoted handles H H', substantially as described.

3. In a folding bed, the section A, provided with side pieces, *a*, having the recesses *i*, the metallic plates *h*, secured to the corners of the 10 section, the legs D, adapted to be folded into the recesses *i'*, the metallic plates *e*, and legs C, substantially as shown.

4. In a folding bed, the section B, provided with side pieces, *c*, having recesses *i'* in their lower edges, the legs D', metallic plates *h'*, attached to the outer ends of the side pieces, the plates *e*, and legs C, the parts being arranged to operate substantially as described. 15

In testimony whereof I do affix my signature in presence of two witnesses.

JOHN McKEOUGH.
